UNITED STATES PATENT OFFICE.

JOHN SEUBERT, OF SIOUX FALLS, SOUTH DAKOTA.

CORN SHREDDING AND HUSKING MACHINE.

1,169,200.

Specification of Letters Patent. Patented Jan. 25, 1916.

Application filed September 12, 1914. Serial No. 861,458.

To all whom it may concern:

Be it known that I, JOHN SEUBERT, a citizen of the United States, residing at Sioux Falls, in the county of Minnehaha and State 5 of South Dakota, have invented certain new and useful Improvements in Corn Shredding and Husking Machines, of which the following is a specification, reference being had to the accompanying drawings.

10 This invention relates to certain improvements in corn shredding and husking machines and has relation more particularly to a machine of the type as disclosed in Patent, No. 735,308, granted to Howard F. Snyder, 15 dated August 4th, 1903; and the object of the invention is to provide a device of this particular character having novel and improved means whereby the stocks or stalks, as delivered upon the husking rollers, are 20 prevented from getting crossed and thereby clogging the machine.

The invention consists in the details of construction and in the combination and arrangement of the several parts of my improved machine whereby certain important advantages are attained and the device is rendered simpler, less expensive and otherwise more convenient and advantageous for use, all as will be hereinafter more fully set 30 forth.

The novel features of the invention will be carefully defined in the appended claims.

In order that my invention may be the better understood, I will now proceed to describe the same with reference to the accompanying drawings, wherein—

Figure 1 is a fragmentary view, partly in elevation and partly in section, of a corn shredding and husking machine, showing an embodiment of my invention in operative position; and Fig. 2 is a fragmentary view in top plan of the husker rollers and husker bars as disclosed in the preceding figure, and illustrating my invention as herein set forth 45 in detail.

As disclosed in the accompanying drawings, 1 denotes the husker rollers, 2 the kicker bars or toothed plates coacting therewith, 3 the feed table, and 4 the husker bars. The 50 foregoing parts are of a form adapted to be mounted and operated in a manner as has been set forth in the prior patent, hereinbefore mentioned, and to which I make no claim.

55 I have found in practice that the corn which is fed into the machine in bundles and

end first, after the binding has been cut, becomes crossed and tangled and materially affects the operation of the machine. To overcome this gross disadvantage, I find it 60 of advantage to have the central bar 4 of a length greater than the remaining bars and terminating at a point rearwardly of the adjacent extremities of the remaining bars with the free end edge thereof perpendicularly disposed relative to the bar, whereby it will be readily perceived that the recurrent movement imparted to such bars will cause the projected or extended portion 5 to serve in the capacity of a divider and automatically cause any of the stocks or stalks which may be disposed crosswise of the machine to assume a requisite position longitudinally of the husker rollers. 65

I have also found in practice that better 75 results can be obtained by having the upper margin of the projected portion 5 tapered upwardly, as indicated at 6, to afford a greater contacting or working edge 7 and with the under edge of the projected portion 80 substantially flush with the under surface or edge of the bar.

It will be observed that, in the operation of the machine, the stalks are thrown directly upon the obliquely inclined edge 7 of 85 the divider bar so that, in the reciprocation of this bar, the said inclined edge 7 will slidingly engage the stalks and thus tend to move the same vertically as they slide downwardly upon the bars 4, thereby effecting the 90 separation of the stalks and disposing the same in parallel relation to the husking rolls.

While it will be readily understood that the extension or projection 5 may be produced integrally with the corresponding 95 husker bar, I disclose such extension or projection herein as in the nature of an attachment, the forward extremities whereof being bifurcated in a vertical plane in order to straddle the adjacent extremity of the husker 100 bar, and in order to maintain such attachment in operative position the transverse attaching means 9 are employed, herein disclosed as conventional bolts with their co-acting nuts.

105 It is to be noted that the widened end portion 6 at its extremity projects above the toothed edge of the lowermost feed bar 2. Thus, in the forward or upward movement of the divider bar, the long end edge of the 110 portion 6 disposed at right angles to the base edge of the divider, will strike the corn

stalks which lie at right angles to said bar and dispose the same in parallel relation to the husking rolls, thus assuring the proper disposition of any of the stalks upon the rolls which may lodge in front of the divider bar.

From the foregoing description, it is thought to be obvious that a machine constructed in accordance with my invention is of an extremely simple and comparatively inexpensive nature and is particularly well adapted for use by reason of the convenience and facility with which it may be assembled and by reason of the effectiveness with which it performs its functions, and it will also be obvious that my invention is susceptible of some change and modification without material departure from the principles and spirit thereof and for this reason I do not wish to be understood as limiting myself to the precise arrangement and formation of

the several parts herein shown in carrying out my invention in practice.

I claim:

The herein described divider bar for corn husking machines consisting of a bar having one end gradually increasing in width to provide a relatively forward edge extending at right angles to the base edge thereof for engagement with the stalks in the forward movement of the bar, the upper edge of said widened portion of said bar being obliquely inclined downward toward the rear end thereof, substantially as and for the purpose described. 35

In testimony whereof I hereunto affix my signature in the presence of two witnesses.

JOHN SEUBERT.

Witnesses:

FRED W. DODGERS,
JOHN C. NASH.
